UNITED STATES PATENT OFFICE.

JEAN BAPTISTE DURAND, OF ST. CHAMOND, FRANCE, ASSIGNOR TO EDMUND AND JOSEPH WRIGHT, CHARLES S. HOWE, AND GEORGE T. MOXEY, OF PHILADELPHIA, PA., AND HARRIS FILSON, OF NEW YORK, N. Y.

RETAINER FOR UMBRELLAS.

SPECIFICATION forming part of Letters Patent No. 336,846, dated February 23, 1886.

Application filed November 12, 1885. Serial No. 182,573. (No model.)

To all whom it may concern:

Be it known that I, JEAN BAPTISTE DURAND, a citizen of the Republic of France, residing in St. Chamond, Loire, France, have 5 invented Improvements in Retainers for Umbrellas, of which the following is a specification.

The object of my invention is to provide an adjustable non-elastic retaining-band for umbrellas; and this object I attain as hereinafter set forth, reference being has to the accompanying drawings, in which—

Figure 1 is a face view, on an enlarged scale, of a retaining-band constructed in accordance 15 with my invention; Fig. 2, a longitudinal section of the same, and Fig. 3 a view of an umbrella provided with my improved retaining-band.

The usual retainers, made of elastic tape or 20 ribbon, for confining the folds of an umbrella are objectionable for the reason that they lose their elasticity after a short time or else become so much stretched by use that they will not properly perform their retaining duty, 25 while an inelastic band or tape is very seldom of the exact length to properly retain the folds of an umbrella, and is also open to the objection that it is liable to stretch somewhat.

My improved retaining-band overcomes 30 this objection, being made of inelastic tape or ribbon capable of adjustment to suit different sizes of umbrellas and to properly retain the folds of the same.

The ribbon or tape F has at one end the 35 usual button, B, and is provided with a ring, A, for adaptation to said button when the band is passed around the umbrella, but this

ring, instead of being, as usual, secured to the end of the ribbon or tape opposite that which carries the button, is adapted to a loop of the 40 ribbon, the end of the latter being secured to the central bar, a, of a buckle, b, which can be moved by hand, so as to lengthen or shorten the loop and consequently increase or diminish the distance between the button B and 45 ring A, thereby adapting the retainer for umbrellas of different sizes and insuring the proper confinement of the folds of the umbrella under all circumstances, the buckle being such that it will not accidentally slip on 50 the band.

The retainer may be separate from the umbrella, if desired, but it is preferable to secure to the umbrella that end of the ribbon F which carries the button B in the usual manner. 55

A hook or projection may replace the button, if desired, and an eye or loop adapted to such hook or projection may be used in place of the ring A, these alternative devices being considered the equivalents of the button and 60 ring.

I claim as my invention—

The within-described retainer for the folds of umbrellas, said retainer consisting of a ribbon, F, combined with the ring A, button B, 65 and sliding buckle b, all substantially as specified.

In testimony whereof I have signed my name to this specification in the presence of two subscribing witnesses.

JEAN BAPTISTE DURAND.
